UNITED STATES PATENT OFFICE.

RUDOLPH C. G. STAATS-OELS, OF BROOKLYN, NEW YORK.

RAZOR-BLADE-SHARPENING DEVICE.

Application filed November 28, 1924. Serial No. 752,548.

This invention relates to improvements in devices for sharpening safety razor blades and the like, and has for one of its objects to provide an improved device of this nature which is simple and practical in construction and by means of which a razor blade may be effectively and easily sharpened.

Another object is to mount the sharpening rollers in the casing or body of the device and to support a razor blade in association therewith in such manner that pressure of the rollers against the blade will be directly proportional to the pressure upon the blade when engaging the latter with said rollers.

Another object is to provide a device which will permit of a blade being engaged with any one of a plurality of sets of rollers of different characteristics with equal facility.

The above and other objects will appear more clearly from the following detailed description, when taken in connection with the accompanying drawing, which illustrates preferred embodiments of the inventive idea.

In the drawing—

Figure 1 is a perspective view of one form of the invention, showing a razor blade in position to be sharpened;

Figure 2 is a transverse section of the device shown in Figure 1;

Figure 3 is a view similar to Figure 2 showing a different form;

Figure 4 is a fragmentary vertical longitudinal section of the form shown in Figure 3; and taken on the line 4—4 of said figure;

Figure 5 is a transverse section of still another form of the invention;

Figure 6 is a diagrammatic view showing the manner in which the blade is engaged by the sharpening rollers;

Figure 7 is a vertical sectional view through one form of blade holder which may be employed in connection with the invention; and

Figure 8 is another form of blade holder.

Referring to the drawing and more particularly to Figures 1 and 2, the device is shown as comprising a rectangular casing 10 made of any suitable material and having a handle 11 projecting from one end thereof which will permit of the device being readily grasped in the hand and adjusted to any desired position when sharpening a blade. Ex-

tending throughout the interior of the casing 10 is a pair of partitions 12. Radially disposed with respect to the longitudinal axis of the casing and intersecting on a line coincident with said axis to provide a plurality of compartments 13, 14, 15 and 16, each of triangular formation.

Contained within the compartments are sets of sharpening rollers 17, 18, 19 and 20 of different characteristics, the rollers 17 and 18 being preferably made of stone and steel, respectively, while the sets of rollers 19 and 20 are covered with different kinds of leather which aid in the sharpening of the razor. The rollers of each set are loosely journaled in the ends of the casing 10 for lateral movement therein with respect to their longitudinal axes so as to permit the rollers of each set to have a certain amount of movement relative to each other. The rollers are normally supported within the casing side by side in the position shown in Figure 2 with their surfaces in engagement with each other and are assisted in maintaining this position by the portions of the partitions 12 which form the inner wall of the respective compartments in which the rollers are mounted and which portions converge inwardly toward the center of the casing.

The outer wall of each of the compartments and which also forms one side of the casing 10 is provided throughout its length with a slot 21 the longitudinal edges of which are inturned to form the flanges 22. The inner edges of said flanges are designed to contact the surface of one of the adjacent sharpening rollers to further aid in supporting the roller in its operative position. The material of which the casing is formed is made sufficiently flexible so that an inward pressure upon any side of the casing adjacent the slot 21 therein will be transmitted through the flanges 22 to the rollers engaged thereby and, owing to the inwardly converging relation of the inner sides of the compartment in which said rollers are mounted, it will be obvious that this pressure will force the rollers into tighter engagement with each other and that this engagement will be directly proportional to the amount of pressure exerted upon the flanges 22.

In accordance with the present invention a safety razor blade 23 or the like is adapted to have the edge to be sharpened insert-

ed through any one of the slots 21 into engagement with the set of rollers in the compartment in which said slot is formed so that edge will come into engagement with the rollers at their point of contact. In this manner the edge of the blade to be sharpened will be interposed between said rollers and owing to the convexity of the latter, it will be obvious that as the blade is reciprocated back and forth longitudinally in the slot 21 the rollers will effect a sharpening of the blade by imparting a hollow ground edge thereto, as clearly shown in Figure 6.

The invention further provides means for holding the blade while being sharpened so that the blade will be maintained in a position perpendicular to the plane extending through the axes of the rollers and intersecting the point of contact therebetween.

In Figure 7 a holder 24 is shown for a blade 25 of a well known make, which blade is provided with one or more openings 26 therein. The holder is formed from a single sheet of suitable material, such as metal, bent upon itself and having its bent portion spaced sufficiently apart to receive the blade 25 therebetween. One side of the holder is provided with one or more projections 27 corresponding in number to the number of openings 26 in the razor blade and adapted to project through said openings and into oppositely disposed openings 28 formed in the opposite side of the holder. The free edges 29 of the holder 24 are curved outwardly, as clearly shown in the various figures, and are designed to engage the side of the casing 10 adjacent the longitudinal slot 21. It will be apparent that, when the blade to be sharpened is inserted into the slot 21 and the edges 29 of the holder engage with the side of the casing adjacent the edges of said slot, inward pressure exerted upon the holder will be transmitted to the rollers through the flanges 22 and in this manner the rollers will be caused to engage the edge of the blade to be sharpened with the desired pressure. The holder and blade may then be reciprocated between the rollers and longitudinally of the slot 21 until a suitable edge has been formed upon the blade. After a blade has been sharpened by one set of rollers the same may be withdrawn and the device turned in the hand to present another set of rollers uppermost and the operation above described may then be repeated.

The holder 30 shown in Figure 8 is of substantially the same construction as the holder 24 and simply shows a slightly different design which will accommodate a blade 31 differing in construction from the blade 25.

In the form of the invention shown in Figures 3 and 4, the casing 32 is again of rectangular formation and made of material having at least a slight degree of flexibility.

In contradistinction to the construction shown in Figure 1 the casing 32 is provided in one side thereof with a longitudinal slot 33. In this instance the ends of the casing 32 have mounted therein a rotatable shaft 34, one end of which projects beyond the adjacent end of the casing and has mounted thereon a milled head 35 which will permit of the operator rotating the shaft in either direction. Supported at each end of the shaft 34 and interiorly of the casing 32 is a disk or plate 36. Journaled in these plates or disks 36 are a plurality of sets of rollers 37, 38, 39 and 40, similar in construction to the sets of rollers 17, 18, 19, and 20, respectively. The rollers of the various sets 37, 38, 39 and 40 are mounted in the plates 36 in such manner that the same will have a slight lateral movement relative to each other and to their longitudinal axes. Each set of rollers is mounted in a compartment formed by the inwardly converging and radially disposed partitions 41 which aid in supporting the rollers in their operative positions. When a set of the rollers, such as the set 38, is in operative position with respect to the slot 33 the flanges 42 formed by the inturned longitudinal edges of said slot engage the rollers so that when pressure is exerted upon the holder 24 the rollers will be forced into tight engagement with the blade to be sharpened as previously described.

In order that any set of rollers may be held in proper position with respect to the slot 33 and prevented from displacement relative to such position by an accidental rotation of the shaft 34, a latch 43 secured to each end of the casing 32 is engaged with any one of the series of notches 44 formed in the periphery of the adjacent disk or plate 36 the spring thus yieldably retaining the disk stationary.

In Figure 5 the casing 45 is also rectangular in formation, but is elongated in cross section as compared to the casings 10 and 32 so that the various sets of rollers 46, 47, 48 and 49, similar to the sets previously described may be arranged in horizontal alignment across the interior of the casing. Again these sets of rollers are journaled in the casing so that the rollers of each set have a slight movement relative to each other and the contacting surfaces of each set are disposed directly beneath a suitable slot 50 extending longitudinally through the top of the casing. The rollers of each set are mounted between two downwardly converging partitions 51 which aid in supporting said rollers and which cause the same to be forced into tight engagement with each other when downward pressure is exerted upon the rollers by the insertion of a razor blade into the associated slot 50. Preferably the adjacent intermediate portions are

formed of single sheets of suitable material bent into inverted V shape, as clearly shown in Figure 5.

The sets of steel rollers 18, 38 and 47 may be provided, at suitable intervals, with annular grooves 52 which permit of the escape from between the rollers of minute shavings from the razor blade as the latter is reciprocated between said rollers.

10 What is claimed is:

1. In a razor blade sharpening device, a casing having a slot therein, the material forming the longitudinal edges of said slot being inturned to provide flanges, partitions 15 in said casing forming a compartment therein and arranged in inwardly converging relation, and a set of sharpening rollers mounted in said compartment and engaged by said inturned flanges so that when pressure is exerted upon the latter said rollers 20 will be forced into tight engagement with each other by the inclination of said partitions relative to each other.

2. In a razor blade sharpening device, a 25 casing having a longitudinal slot therein, a

rotatable shaft extending through said casing, disks carried by said shaft, radially disposed partitions extending between said disks to form compartments, and a set of rollers supported in each compartment by 30 said partitions and capable of being brought into registration with the slot in said casing by rotation of said shaft.

3. In a razor blade sharpening device, a 35 casing having a longitudinal slot therein, a rotatable shaft extending through said casing, disks carried by said shaft, radially disposed partitions extending between said disk to form compartments, a set of rollers supported in each compartment by 40 said partitions and capable of being brought into registration with the slot in said casing by rotation of said shaft, and means engageable with said disks to yieldably maintain each set of rollers in operative position with respect to said slot.

In testimony whereof I have affixed my signature.

RUDOLPH C. G. STAATS-OELS.
